CONCRETE FENCE PANEL

Earle T. Dougherty, 3420 N. 71st Ave.,
Phoenix, Ariz. 85033

Filed Sept. 4, 1973, Ser. No. 394,068

Term of patent 14 years

Int. Cl. D25—02

U.S. Cl. D28—4 A

FIG. 1

FIG. 2

FIG. 3

FIG. 1 is an isometric view of a concrete fence panel showing my design;

FIG. 2 is an enlarged orthographic elevational view of the same; and

FIG. 3 is an enlarged top view of the same.

I claim:

The ornamental design for a concrete fence panel, as shown.
